(57) **CLAIM**

The ornamental design for a double rod clothes rack, as shown and described.

DESCRIPTION

FIG. 1 is a front, left and top perspective view of a double rod clothes rack, showing our design.

FIG. 2 is a rear, right and bottom perspective view thereof.

FIG. 3 is a front view thereof;

FIG. 4 is a rear view thereof;

FIG. 5 is a left side view thereof;

FIG. 6 is a right-side view thereof;

FIG. 7 is a top view thereof; and,

FIG. 8 is a bottom view thereof.

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 2;

FIG. 12 is an enlarged view of portion 12 shown in FIG. 8; and,

FIG. 13 is a perspective view of the double rod clothes rack of FIG. 1 shown in a second state for clarity of disclosure. The dash-dash broken lines in the drawings illustrate portions of the double rod clothes rack that form no part of the claimed design. The dash-dot broken lines represent the bounds of the detail view of the double rod clothes rack and form no part of the claimed design.

1 Claim, 13 Drawing Sheets
